Primary Examiner — Catherine R Oliver-Garcia

(57) **CLAIM**

The ornamental design for the spinning bait holder, as shown and described.

DESCRIPTION

FIG. 1 is a front, right perspective view of a spinning bait holder, showing my new design.

FIG. 2 is a rear, left perspective view of the invention.

FIG. 3 is a right side elevational view of the invention.

FIG. 4 is a rear elevational view of the invention.

FIG. 5 is a left side elevational view of the invention.

FIG. 6 is a front elevational view of the invention.

FIG. 7 is a top plan view of the invention.

FIG. 8 is a bottom plan view of the invention.

FIG. 9 is a left side sectional view of the invention as shown in FIG. 6.

FIG. 10 is a right side elevational view showing the bait holder in an expanded, open configuration.

FIG. 11 is a top plan view of the invention shown in FIG. 10; and,

FIG. 12 is a right side elevational view of the invention attached to a fishing line attached to a hook.

The broken lines in FIG. 12 depict environmental structure and are for illustrative purposes only and form no part of the claimed design.
